UNITED STATES PATENT OFFICE.

JACOB SCHWARZ, OF NEW YORK, N.Y.

CARD-INDEX FILING CABINET.

Application filed September 30, 1925. Serial No. 59,484.

This invention relates to card index filing systems and cabinets therefor, and particularly to the type thereof disclosed in the United States Patent 1,407,948, granted February 28, 1922, to Benjamin G. Rand. This type of card index systems is characterized by the provision of a plurality of cards arranged in overlapping relationship, in shallow, horizontal drawers or shelves, in such a manner that a marginal portion of each card at one edge will be exposed, the exposed marginal portion of each card containing the desired index information and the main body of the card being used for such other information or data as desired. Generally speaking, the cards are pivotally secured in the respective drawers so that any given card may be swung to a position in which information or data contained thereon may be read and amplified or changed or so as to expose a given card to enable it to be read or new data added thereto, such shifting being carried out without requiring the card to be removed from its drawer. Such filing cabinets are usually mounted on a suitable support and it is customary either to use a lower drawer of the cabinet, in a wholly or partly withdrawn position, to support the outer edge of a withdrawn drawer for holding it in an inclined position, or to provide a table or shelf at the front of the cabinet for this purpose. If a lower drawer is used to support a withdrawn drawer the support afforded is not as strong and rigid as might be desired while in constructions in which a table is employed, the uppermost drawers are inclined at such an angle that it is difficult to write upon the cards contained therein. In addition, in either of the above cases, when the cards are swung upwardly against the front face of the cabinet as is required in the use thereof, said cards exhibit a tendency to fall forwardly upon the face of the exposed card. Consequently, it is frequently necessary for the user to hold the upwardly swung card with one hand to prevent their falling forward as above set forth. Again when the cabinet is mounted so that its front extends vertically it is difficult in many cases to read the indicia on the front panels of the lowermost drawers, this difficulty being particularly marked when a front shelf or table is employed.

The principal object of this invention is to provide a new and improved construction particularly adapted for use with a filing

cabinet of an overlapping card type, in which the objections above noted are overcome; the invention contemplates further the provision of a new and improved sectional cabinet construction.

The above and other objects of my invention will appear more fully from the following more detailed description and the features of novelty will be pointed out in the claims.

In the accompanying drawings, which illustrate an example of the invention, without defining its limits, Fig. 1 is a front elevation of the novel sectional cabinet, Fig. 2 is a plan view thereof, Fig. 3 is a rear elevation; Fig. 4 is a side elevation of the structure shown in Fig. 1; and Fig. 5 is a perspective of a supporting frame unit.

As shown in the drawings, the sectional cabinet of Figs. 1 to 4 inclusive, comprises a plurality of supporting units one of which is shown in Fig. 5 and is designated generally by the reference character A. The supporting units, which may be of any suitable construction, are shown as consisting of a pair of side castings or frames each having vertically extending front and back legs 10 and 11 respectively, the upper extremities of which are connected by a downwardly and rearwardly inclined supporting bar or member 12. The side frames are connected and held together in properly spaced relationship by means of the connecting bars 13 and 14 and a horizontal supporting plate 15 projecting upwardly beyond the inclined bars 12 in the form of a flange 15' which is substantially perpendicular to the plane of said inclined supporting bars 12. The side frames are provided, at the front thereof, with forwardly projecting table brackets 16, preferably comprising integral parts of said frames, and constituting supports for a table 17, said table extending between the side frames and assisting to secure the side frames in connected spaced relationship.

The legs 10 and 11 and the supporting bars 12 are preferably of angle iron configuration so that when the supporting units A are assembled, the outer side faces thereof present plane surfaces which enable two or more of such units to be bolted or otherwise detachably secured together to form an assembled structure consisting of any desired number of units as shown in Figs. 1 to 4. To facilitate this interconnection of said units A, each of the side frames is provided

with a plurality of holes 18 similarly located in each frame so that such holes will align with the correspondingly located holes of any other side frame, thus enabling two or more frames to be readily bolted together. It will be understood that the frame units and the cabinets carried thereby are of the same width so that the side walls of each cabinet will be in the same vertical plane as 10 the outer wall of each frame unit.

The filing cabinets per se are indicated generally by the reference character B, and each of said cabinets consists of a rectangular outer casing 20 containing a plurality of 15 drawers or slides 21 to which the cards 22 are pivotally and detachably connected by any suitable means which form no part of the present invention.

The cabinets are placed upon the supporting bars 12 of the frame units with their 20 lower rear ends supported by the flange 15^a of the supporting plate 15, as shown most clearly in Fig. 4, the fronts of the cabinets being inclined rearwardly and upwardly, and 25 preferably at an angle of approximately 45° to the vertical although a smaller angle, for example 30° would suffice.

Side brackets 23 and 24 may be provided for supporting the side shelves or table sections 25, said brackets having the vertical legs thereof provided with holes arranged to align with certain of the holes 18, for the accommodation of bolts or other suitable devices for connecting said side brackets and 35 their table sections with the terminal units A of the assembled structure as shown in Figs. 1 and 3.

When only one frame unit and cabinet is used, the side shelves and brackets are bolted 40 preferably to each side of the single frame unit. In both cases the side brackets serve as means to hold the cabinets against movement transversely of the supporting frame. It will also be understood that, while the 45 provision of the side tables 25 is preferable because of the extra table space secured by their use, any means may be substituted therefore to act as side stops for preventing transverse movement of the cabinet units.

50 It will be noted that when the cabinets are supported and arranged as herein disclosed, the entire fronts of the cabinets are located at an inclination directly in the field of vision of the user, thereby enabling the 55 user to read the data contained on the front panel of any cabinet drawer without necessitating any stooping or change from an upright position on the part of such user. In addition when a drawer is withdrawn and 60 supported on the front table in the manner shown in Fig. 4, it is firmly maintained in a most advantageous position for examining a given card and for writing thereon; in addition any desired number of the uppermost 65 cards may be thrown upwardly against the

front of the cabinet to positions well beyond the vertical plane of their pivotal supports so that the possibility of such cards falling forwardly upon the exposed card is practically obviated. Consequently the user will 70 not be required to manually maintain such top cards in their upper position, as a result of which both hands are free and said user is enabled to work with greater speed and efficiency. 75

It will be understood that various changes in the constructional details herein disclosed may be resorted to without departing from the spirit of my invention, for example, the 45° angle of inclination of the cabinets 80 shown is merely illustrative, likewise the construction of the frame units as shown may be departed from. In addition the invention is not limited to the construction of sectional cabinets although the sectional 85 construction is preferable.

I claim:

1. In a card index filing cabinet, a supporting unit provided with a table and an inclined support extending rearwardly and 90 downwardly from said table; and a cabinet unit having a plurality of drawers adapted to contain index cards slidably mounted therein, supported on said inclined support with the front of said cabinet extending 95 rearwardly and upwardly from said table.

2. The combination with a card index cabinet unit of the type having a plurality of drawers slidably mounted within the cabinet, and pivotally movable relatively 100 thereto, in their withdrawn positions, said drawers being adapted to have a plurality of cards pivotally mounted therein arranged in superimposed overlapping relationship, of a supporting unit provided with a forwardly extending table and an inclined support for said cabinet extending rearwardly and downwardly from the top of said table and additional supporting means to hold said cabinet on said inclined support with 110 the front of said cabinet extending rearwardly and upwardly from the top of said table, said table cooperating with said pivotal connection of a drawer to support said drawer when withdrawn from said cabinet. 115

3. The combination with a card index cabinet unit of the type having a plurality of drawers slidably mounted within said cabinet, said drawers being adapted to have a plurality of cards pivotally mounted therein arranged in superimposed overlapping relationship, of a support for said drawers when withdrawn from the cabinet, and of a supporting unit provided with an inclined support extending rearwardly and downwardly from the front edge of said unit, said support being adapted to hold said cabinet with its front face inclined rearwardly and upwardly. 120

4. The combination with a plurality of 1 1

filings cabinet units of the type having a plurality of drawers slidably mounted within said cabinet units, said drawers being adapted to have a plurality of cards mounted therein arranged in horizontal, superimposed, overlapping relationship, of a supporting frame for said cabinets consisting of 25 a plurality of supporting units detachably connected with each other, each of said supporting units being of the same width as a cabinet unit and being provided with supports to hold a cabinet unit with the front face thereof inclined rearwardly to the vertical and means secured to the outer faces of the 30 terminal supporting units to prevent movement of said cabinet units transversely of said support, said means comprising a 35 bracket and a side table secured thereto.

5. The combination with a plurality of filings cabinet units of the type having a plurality of drawers slidably mounted within

In testimony whereof I have hereunto set my hand.

JACOB SCHWARZ.
